Howson & Howson

UNITED STATES PATENT OFFICE.

BROWNELL BUEHLER, OF PHILADELPHIA, PENNSYLVANIA.

BEATING-ENGINE.

1,271,426.

Specification of Letters Patent.

Patented July 2, 1918.

Application filed January 22, 1918. Serial No. 213,222.

To all whom it may concern:

Be it known that I, BROWNELL BUEHLER, a citizen of the United States, residing in Philadelphia, Pennsylvania, have invented 5 an Improvement in Beating-Engines, of which the following is a specification.

My invention relates to engines for beating up or pulping stock such as old paper, for use in the manufacture of box board for 10 example, and one of its objects is to employ certain structures and spaces not ordinarily utilized, for the purpose of separating and withdrawing the stock as soon as it has been reduced to pulp whose pieces are of the required size.

It is further desired to provide a machine of the type noted with a novel form of perforated structure and outlet chamber for withdrawing the pulp from the tank, the 20 invention contemplating the perforation of the backfall and the connection of the outlet pipe of the machine to the inclosed space immediately under said part.

These objects and other advantageous ends 25 I attain as hereinafter set forth, reference being had to the accompanying drawings, in which—

Figure 1 is a longitudinal vertical section of a beating engine including my invention, 30 Fig. 2 is a plan of the machine shown in Fig. 1, and

Fig. 3 is a perspective of the backfall.

In the above drawings, 1 represents the 35 construction, having rotatably mounted between its central partition 2 and one of its sides, a beating roll 3 carried on a shaft 4 supported in suitable bearings 5 and 6. Fixed to the shaft 4 is a driving pulley 4^a 40 which, under operating conditions, is driven from any suitable source of power.

The roll or drum 3 has projecting from its surface blades or knives 7 designed to co-act with a fixed member 8 supported in 45 the customary manner at the bottom of the tank by a frame 9 and a backfall 10 extends upwardly adjacent to but at an increasing distance from the surface of the roll, having its upper outer end carried to a height 50 slightly below the level of the center line of said roll, from whence it extends back and downwardly at an angle of about 45° to the bottom of the tank.

As indicated, the outlet pipe 12 leading 55 to any desired receptacle such as a stuff

chest, is connected to the space defined by back fall 10, the downwardly extended cover portion 11 thereof and the bottom of the tank immediately under these parts, and there are perforations 13 formed through 60 the backfall into the chamber 14. These openings are of the dimensions necessary to separate stock which has been reduced to pieces of pre-determined size and forms a pulp, from the larger pieces of stock. 65

Under operating conditions, rotation of the beating roll 3 in the direction of the arrow *a* Fig. 1, causes a circulation of water and stock in the tank in the direction of the arrow *b*, the valve 15 in the pipe 12 being 70 opened sufficiently to permit of a flow of pulp from the space 14 under the backfall at the desired rate to the stuff chest or other receptacle. Owing to the co-action of the blades on the roll with the fixed member 8, the stock is reduced to pulp and as this is formed the greater portion of it is continuously removed from the tank by passing through the perforations 13 in the backfall, it being noted that the stoppage of said 75 perforations by larger pieces of stock is effectually prevented by the washing action of the liquid current passing at relatively high velocity over the concave face of said backfall or equivalent structure. 80

By reason of the above described arrangement and operation of the parts, I am enabled to utilize what is ordinarily a waste space in the beating engine, to wit,—that space under the backfall 10 and inclined 90 cover 11.

It is to be understood that while for purposes of illustration I have shown my invention as applied to a machine technically known as a beating engine, it may without material alteration be employed in apparatus such as washing machines in which the roll is utilized for purposes of circulation or agitation of the stock either with or without the fixed member or bed plate 8. 95

I claim:

1. The combination in a beating engine of a tank; a circulating roll; a backfall mounted in the tank adjacent said roll and having perforations therein of a size to permit passage of pulp; and means for withdrawing from the tank the pulp passing through the perforations of said backfall. 105

2. The combination in a beating engine of a tank; a beating roll therein having blades; 110

a fixed member mounted in the tank to co-operate with the blades of said roll; a concave backfall extending upwardly adjacent the roll from a position near the fixed blades 5 and having perforations therein of a size to permit passage of pulp; an extension coöperating with the bottom of the tank and

the backfall to define a closed chamber; and a conduit connected to said chamber for withdrawing therefrom the water and pulp 10 passing through the perforations of the backfall.

In witness whereof I affix my signature.
BROWNELL BUEHLER.
